UNITED STATES PATENT OFFICE

2,519,854

PENCIL SHARPENER

Franz Schär, Thun, Switzerland

Application September 30, 1948, Serial No. 51,876
In Switzerland October 7, 1947

1 Claim. (Cl. 120—93)

1

This invention relates to pencil sharpeners having a stop for determining the length of the point. Sharpeners of this type are already known in the art. However, up till now, these stops had no influence whatever on the shape of the lead point and therefore the pencil points obtained by these known sharpeners always required a finishing cut to be taken for giving them the shape desired for use which, as is well known is not identical with the conical shape obtained by means of the sharpener blades.

The pencil sharpener according to the invention is characterised in that the stop is formed by a lead file.

By preference, this lead file may be mounted rotatably around an axis parallel to the pencil guide. Furthermore, the lead file may be arranged to be axially adjusted.

Other objects and features will be apparent as the following description proceeds, reference being had to the accompanying drawing illustrating by way of example one embodiment of the invention and wherein

Fig. 1 is a side view of the pencil sharpener, partly in section, and

Fig. 2 is front view thereof.

As in devices of known type, the pencil sharpener comprises a sharpener body 1 in the middle portion of which a pencil guide 2 is provided along the one side of which the blade 3 is mounted. At the side of the guide 2 opposite to the blade 3 a pin 4 is slidably arranged in the body 1 parallel to the guide 2. To the end of the pin 4 projecting from the sharpener body a disc-shaped file 5 for finishing the lead point of a pencil is fixed. This lead file 5 has a fluted rim 6 and a conical file surface 7. However, this file surface 7 may have any other shape if desired for special purposes. The circular front face of the file, as shown in Fig. 2, may serve as a second file surface which neither forms a stop nor can it be used for filing leads of pencils when guided in the guide 2 during sharpening; this second circular file surface can only be used for taking the finishing cut on other leads. A set screw 8 serves the purpose of holding fast or locking the pin 4 together with the lead file 6 in a certain position. An adjusting screw 9 screwed into the body 1 lies coaxial to the pin 4 and contacts this latter by one of its ends, so that on turning the screw 9 the pin 4 with the lead file 5 may be axially adjusted in one direction.

As soon as, on sharpening, the lead of the pencil to be sharpened has been denuded of the wooden envelope up to a certain length, the fore

5 end of the lead strikes against the surface 7 of the lead file 5, thereby determining the length of the lead point and giving this latter at the same time the shape desired by a filing operation of the surface 7. Should it be desired to have a longer lead point, the distance between the end of the body 1 and the lead file 5 can be increased by turning the adjusting screw 9. Should another shape be given to the lead point, the lead file 5 and the pin 4 may be removed and replaced by another file having the new shape desired for the lead point.

10 While I have described and illustrated one embodiment of my invention, I do not wish to unnecessarily limit the scope of this invention, but reserve the right to make such modifications and rearrangements as may come within the purview of the accompanying claim.

15 What I claim is:

20 In a pencil sharpener, a body member comprising a pencil guide hole in its middle portion, a blade fixed to said body member at the one side of said pencil guide hole, a pin slidably and rotatably mounted on said body member at the 25 side of said pencil guide hole opposite to said blade, one end of said pin projecting from said body member, a disk-shaped file fixed to the projecting end of said pin and provided with a conical file surface lying in front of said pencil 30 guide hole to serve as a stop for the pencil and as a tool to give the lead point of the pencil the shape desired, a set screw screwed into said body member radially with regard to the axis of said pin to lock the latter in position, and an adjusting screw screwed into said body member coaxially to said pin and in engagement with said pin to allow axial adjustment of said file surface in one direction.
